UNITED STATES PATENT OFFICE.

LOUIS BOLLMAN, OF NEW YORK, N. Y.

CONDENSER FOR STEAM-ENGINES.

Specification of Letters Patent No. 12,619, dated April 3, 1855.

To all whom it may concern:

Be it known that I, Louis BOLLMAN, of the city, county, and State of New York, have invented certain new and useful Improvements in Condensers for Steam-Engines; and I do hereby declare that the following is a full, clear, and exact description of the same, reference being had to the accompanying drawings, forming part of this specification, in which

Figure 1, is a vertical central section, of a condenser having my improvements. Fig. 2, is a vertical section at right angles to Fig. 1, in the line x, x . Fig. 3, is a vertical section at right angles to Fig. 1, in the line y, y . Fig. 4, is a vertical section through the center of the injection tubes and valve.

Similar letters of reference indicate corresponding parts in the several figures.

This invention relates to that description of condensers in most common use, generally known in contradistinction to the surface condenser, as the wet condenser.

The first part of my invention consists in a certain method of regulating the injection of cold water into the condenser by the state of the vacuum, whereby, without injecting a much greater quantity of water than is necessary to condense the steam I am enabled to produce a vacuum very quickly so as to obtain its full effect, as nearly as possible during the entire stroke of the piston of the engine.

The second part of my invention consists in heating to a much higher temperature than the water which is drawn from the condenser, a sufficient quantity of water to feed the boiler, by proper means of injecting the said quantity of water at the commencement of the eduction of the steam, into the eduction passage or cylinder, and withdrawing it quickly therefrom into a suitable receiver, which, after receiving it, and before the pressure in the condenser is much reduced, is shut off from the condenser to prevent the loss of the heat of the water by its boiling in a vacuum.

To enable others skilled in the art to make and use my invention I will proceed to describe its construction and operation.

A, is the body of the condenser, and B, C, is the eduction passage from the cylinder. E, is a small piston fitting air tight into a small open cylinder D, so arranged below the eduction passage that the top of the piston, is exposed to the pressure of steam in

the condenser, and the bottom to the pressure of the atmosphere. F, is the injection pipe leading to a valve chamber G, outside the condenser. This valve chamber contains a disk-valve I to open and close the entrances e, e , (see Fig. 4) to the two perforated injection tubes H, H, which extend the whole length of the condenser. The valve I, is attached securely to a spindle J, which runs through the condenser and valve box, and has journals fitting to suitable bearings therein, and which carries a forked arm K, which embraces the rod a , of the piston E, between two stops c, c . The forked arm K, has a spring b , applied to it in such a way as to draw it downward.

The piston E, and the valve I, serve to regulate the injection of water into the condenser by the state of the vacuum and when the engine is in operation they act in the following manner: I will suppose the eduction of the steam from the cylinder to commence, and that previous to its commencement there is a vacuum in the condenser equal in value to one pound pressure on the square inch. The piston E, will be at that time forced upward by the pressure of the atmosphere with a force about equal to $15-1=14$ pounds per square inch, and this force will be balanced by the tension of the spring b so as to be in such a position as to hold the valve I, stationary in position to close the entrances e, e , to the injection tubes H, H. This position of the piston will be somewhat higher than that shown in red outline in Fig. 2. When the eduction commences and the steam begins to enter the condenser, the vacuum will be destroyed, and the atmospheric pressure will be insufficient to hold up the piston E, which will be forced downward by the action of the spring b , until it reaches the position shown in black outline in Fig. 2, in which position it is arrested by the lower stop c , on the piston rod coming in contact with the guide d . In this position of the piston the valve I, opens the water passages e, e , fully to inject the water into the condenser. In a short time the pressure in the condenser will be reduced, and the atmospheric pressure will gradually force up the piston again till it closes the water passages e, e , and brings the apparatus into the same condition in which it was first described.

By this method of regulating the injection I obtain the following advantages over

the system of injecting in a continuous stream as commonly practiced. 1st: Less injection water will be required. 2nd: A smaller air pump and condenser may be used. 3rd: The vacuum will be produced earlier in the stroke. 4th: The engineer will be relieved of all care of the injection cock. 5th: However the speed, action or condition of the engine may vary, the injection will be always accurately regulated in accordance therewith. In explanation of these advantages I will offer a few remarks. In common condensers, the continuous stream of water which is injected increases in velocity when it is least required, viz, toward the end of the stroke of the engine when the vacuum arrives nearer to a state of perfection; but I only inject when it is required, and am enabled to inject a much greater quantity at the commencement of education to effect condensation more quickly and still use much less water; thus I gain power by obtaining the vacuum earlier in the stroke of the engine and save power by having less water to pump from the condenser. It is obvious that as the area of the opening of the injection passages *e*, *e*, is proportionate in or nearly in the direct ratio to the pressure in the condenser or in the inverse ratio to the vacuum the injection must be properly regulated under all circumstances without any attention from the engineer.

The stoppage of the injection when the air pump is disabled or the diminution in its quantity when the pump works imperfectly is effected by means of a disk valve *L*, (see Fig. 4) working between the valve *I*, and the back of the valve chamber which contains the passages *e*, *e*. This valve turns loosely on the spindle *J*, so as to be independent of the valve *I*; and it carries an arm *M*, to which is attached a float *N*, which will fall to the bottom of the condenser when there is no considerable quantity of water in the latter, but rise with any accumulation of water in the condenser and cause the valve *L*, to partly or entirely close the injection passages *e*, *e*. It often happens that some particles of matter coming between the valves of the air pump and their seats will prevent the proper action of the air pump and destroy the vacuum in the condenser. In that case the valve *I*, before described would not be closed by the pressure of the atmosphere on the piston and too much water might enter the condenser and cause disarrangement of the engine and danger of breaking the cylinder of the engine by water flowing into it. This will be effectually obviated by employing the valve *L*, controlled by a float in the condenser.

The heating of the feed water and withdrawing it from contact with the steam in the condenser will now be described.

P, is a small injection pipe entering the eduction pipe *B*; *Q*, is a small receiver below the eduction passage *C*, which leads into the condenser, and *S*, is a pipe for supplying the feed or hot water pump from the receiver. The receiver, communicates with the passage *C*, through a cylindrical opening *R*, which is directly above the cylinder *D*, so that the piston *E*, may fit and work within it. It has been before stated that at the time the eduction commences the piston *E*, is down. In that position of the piston there is a free communication between the receiver *Q* and the exhaust passage, as the piston does not reach the opening *R*. The feed water, the necessary quantity of which is only estimated at about one twenty eighth part ($\frac{1}{28}$) of the quantity necessary to effect condensation, is to be injected in finely divided streams from the pipe *P* at the commencement of eduction by opening a valve or cock of some description and closing it as soon as sufficient has been injected. The valve or cock for this purpose I have not thought necessary to represent, as it may be of any description capable of opening and closing a pipe. Suffice it to say, that the opening and closing must be effected by the engine itself, by gearing from the shaft or otherwise, and that this injection must be effected during a very small portion of the stroke. When the head pressure of this injection water is not sufficient to force it into the escaping steam, a force pump must be employed to drive it through the pipe.

At the time of the termination of the injection of the feed water the temperature in the condenser will have been reduced only a few degrees; as the water is heated mostly by the latent heat, which is about five sixths ($\frac{5}{6}$) of the entire heat of the steam, it may be heated to nearly the same temperature as the escaping steam. The particles of water passing along with the steam will rush through passage *R*, into the receiver *Q*, and to facilitate this, the lower end *f*, of the eduction pipe is contracted, and the mouth *g*, of the opening *R*, expanded, into funnel shape, so that the former nearly enters the latter. In order to expose a large surface to collect the minute particles of water, the receiver may contain a great number of wires. The passage *R*, only remains open as long as there is a considerable pressure in the condenser and eduction passage, as it is closed when the pressure has been reduced to a certain degree, by the piston *E*, entering the passage *R*, as shown in red outline in Fig. 2, in its before described operation to regulate the supply of injection water to the condenser, some time before the vacuum is produced. This shutting off the receiver from the condenser prevents the exposure of the heated water to the vacuum, in which it

could not exist above a certain temperature without being again converted into steam. The feed water might be injected directly into the cylinder or even into the receiver

5 Q. Its injection should in all cases cease at or before the time of closing the passage R. Water for this purpose may be taken from the hot well of the air pump which will have a temperature of about 100°, previous to its 10 injection. The quantity of water thus injected may be greater than is required for the boiler in order to supply a certain quantity for any purpose requiring it of a higher temperature than it leaves the condenser 15 through the air pump. It is not necessary that the shutting off the receiver Q, from the condenser, should be effected by the piston E; but I have shown that method of effecting it, as being very simple when the 20 piston is employed for the purpose herein first specified. The same result may be effected by a slide valve operated by proper gearing from the engine shaft or other part of the engine to open and close the passage 25 at the proper time as described.

The advantage resulting from this method of heating the water to supply the boiler will be a considerable saving of fuel. The water may be thus heated to a temperature 30 of about 200° or 100° hotter than the water supplied from other condensers, the entire quantity of heat to be supplied by the fuel when the feed water is 100° being $1100^{\circ} - 100^{\circ} = 1000^{\circ}$, while in this case it is only 35 $1100^{\circ} - 200^{\circ} = 900^{\circ}$. In addition to the above a further saving will be effected in the following manner. It is well known that the steam always carries more or less water from the boiler in consequence of priming, 40 so that in practice the feed water required is found to be double the quantity theoretically shown to be sufficient in a perfect apparatus. In common condensers the heat of this water is lost, but in my condenser this water will

pass into the receiver Q, and be carried back 45 to the boiler nearly at the same temperature as it left. In the same manner the water condensed from the steam by contact with the surfaces in its passage from the boiler to the cylinder is saved.

50 What I claim as my invention and desire to secure by Letters Patent, is—

1. The within described method of controlling the injection of cold water into the condenser by connecting the injection cock 55 or valve with a piston E, or its equivalent, which is exposed on one side to the pressure of the atmosphere and on the other to the pressure within the condenser, and is acted upon substantially as herein set forth by 60 variations in the pressure in the condenser so as to increase or diminish the injection as the said pressure diminishes or increases and to stop the injection when the desired vacuum is obtained.

65 2. The employment substantially as herein described for the purpose of heating a sufficient quantity of water to supply the boiler, to a higher temperature than the water delivered by the air pump, of an additional injection pipe P, to inject the said quantity of water at the commencement of eduction into the eduction pipe or passage, the cylinder or any convenient place near the entrance to the condenser, combined with 70 a receiver Q, which is arranged in any way substantially as described and furnished with any suitable means substantially as described of opening it at the commencement of eduction and injection, to receive the said 75 water, and of shutting it off from the condenser before the temperature of the latter is too much reduced.

LOUIS BOLLMAN.
